UNITED STATES PATENT OFFICE

2,119,386

FLOOR POLISHING MACHINE

Osmund Holm-Hansen, Stratford, and Noble H. Watts, Bridgeport, Conn., assignors to General Electric Company, a corporation of New York

Application August 28, 1934, Serial No. 741,840

9 Claims. (Cl. 15—49)

Our invention relates to polishing machines for polishing floors and the like.

An object of our invention is to provide a compact polishing machine which may be used under furniture and in other places having small clearance.

Another object of our invention is to provide an improved arrangement for detachably fastening the polishing elements to the driving spindles.

10 Further objects and advantages of our invention will become apparent as the following description proceeds.

In the drawing Fig. 1 is a perspective view of a polishing machine embodying our invention; Fig. 2 is an enlarged perspective view of the handle and the latch for latching the handle in position; Fig. 3 is a sectional view of the driving mechanism for the polishing elements; Fig. 4 is a side elevation, partly in section, of the polishing machine; 20 Fig. 5 is a fragmentary plan view of the polishing machine; and Fig. 6 is a fragmentary sectional view of the polishing machine with polishing elements for final polishing.

Referring to the drawing, the polishing machine comprises polishing elements or brushes 2 which are driven through reduction gearing contained in an enclosed casing 1 by a horizontal shaft motor 3 attached to the rear of the casing 1 and extending rearwardly from the casing in substantially the same plane as the casing. A handle 4 is pivotally attached at 5 to the motor 3 for guiding the machine over a floor or other surface to be polished. Since there are no rolls to support the machine, the entire weight of the 30 polishing machine is supported on the brushes 2 which increases the effectiveness of the polishing and no marks are made on the floor. As the motor 3 extends horizontally from the casing 1, the polishing machine can be used under furniture or in other places where the vertical clearance is small.

The casing 1, in which the driving mechanism for the brushes is located, comprises a concave shell 1a having ridges 6 at the front and depending sides 7 to which a plate 8 is secured by screws fitting into lugs 9. The lugs 9 are disposed at intervals about the inner surface of the depending sides 7. A gasket 33 arranged about the edges of the plate 8 is compressed against a shoulder 9a on the shell 1a and provides an oil-tight joint. The motor 3 is attached to the rear side of the shell 1a by studs 29 and extends longitudinally in substantially the same plane as the shell. The motor has a horizontal shaft 26 which extends within the casing 1 and

is journaled in a bearing 27 which is carried in a bearing support 28 formed integrally with the shell 1a. A worm 25 is attached to the end of the shaft 26. The plate 8 is provided with four integral tubular bearing supports 10, 11, 12 and 13 which extend vertically above and below the plate. A bearing 14 is arranged in each of the bearing supports. Each bearing extends slightly above the upper end of the bearing support and is provided at its lower end with a shoulder 15 which 10 engages the lower end of the bearing support. Four vertical spindles 16, 17, 18 and 19 are journaled in the bearings 14. Each of the inner spindles 17 and 18 has attached to its upper end a cone-shaped member 21 having a worm wheel 22 15 on its outer periphery which meshes with the worm 25 secured to the motor shaft 26. As the motor shaft turns, the spindles 17 and 18 are rotated in opposite directions. A conical shaped cup 23 attached to the inner surface of each of the worm wheels 22 carries oil from depressions 34 in the plate 8 to the inner surface of the worm wheel from which the oil is thrown by centrifugal force through holes 24 to lubricate the worm gear 25. Oil slingers 20 are attached to upper ends 20 of spindles 16 and 19 and prevent leakage of oil around these spindles.

Clutch members or holders 35, 36, 37, and 38 for receiving the polishing elements are respectively connected to the lower end of each of the spindles 16, 17, 18, and 19. Each of these holders comprises a metal cup 39 which is threaded on the end of the spindle and has an annulus 40 of resilient material such as rubber molded around the depending rim. The inner surface of the 35 annulus of rubber is tapered to provide a conical clutch surface for frictionally engaging the conical surface 42 of the polishing elements. The outer surface of the rubber is cylindrical and the outer surface of the rubber on holders 36 and 37 40 frictionally engages the outer surface of the rubber on holders 35 and 38 and forms a friction drive between the spindles 16 and 17 and the spindles 18 and 19 respectively. The inner conical surface of the rubber provides a convenient 45 clutch for holding the brushes or polishing elements 2 from which the brushes may be readily removed.

The spindles 17 and 18 are rotated in opposite directions by the motor shaft 26 and the outer 50 spindles 16 and 19 are rotated in opposite directions by the clutches 36 and 37. Adjacent polishing elements are therefore driven in opposite directions. The threads on the spindles 16, 17, 18, and 19 are arranged so that the holders 35, 36, 55

37, and 38 tend to tighten on the spindles as they are rotated. As the machine is supported by the polishing elements, this manner of rotating these elements tends to prevent the machine from 5 turning on the floor or other surface to be polished. Lugs 41 which are positioned on the casing 1a over spindles form stops which prevent the spindles from dropping into the inner compartment of the casing when the casing is turned 10 upside down, and the clutches are unthreaded from the spindles.

The handle 4 has at its lower end arms 45 which are pivotally attached at 5 to the motor 3. Instead of being freely pivotable, however, the 15 handle is arranged to be latched in a number of fixed angular positions. This arrangement of the handle allows the machine to be supported on the brushes and makes additional support for the machine unnecessary. The relatively small 20 brushes provide a narrow line of contact and permit wide variation in the angle of the polisher to the floor without interfering with the operation of the machine. In the surface of the motor frame, there are provided slots 43 in which a 25 spring-pressed latch 44 disposed within the handle is adapted to be positioned to hold the handle in one of a number of fixed angular positions. The upper ends of the arms 45 are threaded to receive a union coupling 46 which 30 joins the arms to the handle 4. Disposed within the passageway formed when the arms 45 are thus joined to the arm 4 is a split latch casing 47. This latch casing is provided with shoulders 48 which engage the arms 45 and prevent the latch 35 casing being moved. The latch 44 is disposed within the latch casing and a compression spring 49 normally presses the latch downwardly into engagement with one of the slots 43. A lever 50, pivoted at 51 and extending through an opening 40 in the latch casing 47 is provided for moving the latch out of the slots 43 against the action of the spring 49.

A conductor 52 adapted to be connected to a source of electrical supply and containing the 45 conductors 53 and 53' is introduced into the hollow handle 4 through an opening adjacent the switch 54. The conductors 53 and 53' are led through the handle 4 and connected to binding screws 55 on opposite sides of the latch casing 47. 50 As the latch casing fits snugly within the arms 45, the casing is cut away to provide clearance for the conductors 53 and 53'. These conductors are connected to the motor. The end of the handle 4 is provided with a hand grip 58 for the convenience of the operator.

In Fig. 6, the polishing machine is shown equipped with two polishing elements each having a felt polishing disk 61 of larger diameter than the brushes 2 which is suitable for final 60 polishing. The felt disk is loosely attached to the lower side of a rubber holder 62 by a pin 63 having a split shank which extends through the center of the felt disk 61 and through a hole 64 in the center of the neck portion 65 of the holder. 65 The head of the pin and the portion of the felt disk around the head are drawn within a recess 66 in the lower side of the holder, and the upper ends of the split shank which project above the upper surface of the neck 65 are bent outwardly 70 to hold the pin in place. The pin 63 loosely fastens the felt disk to the holder 62 so that the disk remains in position on the holder when the machine is lifted from the floor. When the machine rests on the floor, the felt disk is driven by 75 frictional engagement with the lower surface of

the disk portion 67 of the holder which is of friction material such as rubber and molded integrally with the lower end of the neck 65. The disk portion of the holder is reinforced and maintained in a flat condition by a metal disk 68 which is embedded therein. The inner edge 69 of the disk 68 is bent upwardly and extends into the neck 65 to reinforce the connection between the neck and disk portions of the holder. The outer edge 70 of the disk 68 is turned up to provide a reinforced edge. From the upper edge of the neck 65 of the holder, integral rubber walls 71 flare outwardly and upwardly to a hollow hub 72. A metal ring 73, having a serrated inner surface 74 molded to the outside of the hub 72, 15 has a tapered outer surface which is adapted to engage the tapered inner surface of holders 35 or 38 to complete the driving connection to the polishing element in the same manner as the tapered surface 42 of brushes 2. The walls 71 20 of the holder provide a flexible universal joint connection which allows the felt disks to be maintained in contact with the floor through a wide variation in the angle of the polisher to the floor. The polishing element shown in Fig. 6 can be 25 used for sanding by substituting a sand paper disk for the felt disk illustrated.

Although we have shown a particular embodiment of our invention, we do not desire to be limited to the construction described, and intend in the appended claims to cover all modifications which do not depart from the spirit and scope of our invention.

What we claim as new and desire to secure by Letters Patent of the United States, is:

1. In a polishing machine, a vertical spindle, means for driving said spindle, a holder secured to the lower end of said spindle, said holder having an annulus of resilient material with a tapered surface, and a polishing element secured to said holder by frictional engagement with said tapered surface.

2. In a polishing machine, a vertical spindle, means for driving said spindle, a holder secured to the lower end of said spindle, said holder having an annulus of resilient material, and a polishing element secured to said holder by frictional engagement with the inner surface of said annulus.

3. In a polishing machine, a vertical spindle, means for driving said spindle, a holder secured to the lower end of said spindle, said holder having an annulus of resilient material with a tapered inner surface, and a polishing element having a complementary tapered surface secured to said holder by frictional engagement with said inner surface.

4. In a polishing machine, a vertical spindle, means for driving said spindle, a holder secured to the lower end of said spindle, and a polishing element, said holder and said polishing element having complementary tapered surfaces at least one of which is formed of resilient material for holding said polishing element in said holder.

5. A polishing machine comprising a casing 65 having two vertical spindles rotatably carried therein, a holder secured to each of said spindles, said holders having an annulus of resilient material with a tapered inner surface, the outer surfaces of resilient material on each holder being in 70 frictional engagement, said holders being adapted to hold a polishing element by frictional engagement with said tapered surface, and means for driving one of said spindles.

6. In a polishing machine, a vertical spindle, 75

means for driving said spindle, a metal cup secured to said spindle and having a depending rim, an annulus of rubber having a tapered surface secured to said rim, and a polishing element secured to said spindle by frictional engagement with said tapered surface.

5. A polishing machine comprising a casing having two vertical spindles rotatably carried therein, a metal cup having a depending rim secured to each of said spindles, an annulus of rubber having a tapered inner surface secured to each of said rims, the outer surfaces of each annulus of rubber being in frictional engagement, a polishing element secured to each of said spindles by frictional engagement with the inner surface of each annulus, and means for driving one of said spindles.

7. A polishing machine, a vertical spindle, means for driving said spindle, a clutch member secured to the lower end of said spindle, said clutch member having an annulus of resilient material with a tapered surface, a polishing element, a rubber holder for said polishing element

having a hub secured to said clutch member by frictional engagement with said tapered surface and having flexible walls below said hub for permitting alignment of said polishing element with the surface being polished.

9. In a polishing machine, a vertical spindle, means for driving said spindle, a clutch member secured to the lower end of said spindle, said clutch member having an annulus of resilient material with a tapered surface, a rubber holder 10 for a polishing disk having a hub secured to said clutch member by frictional engagement with said tapered surface and having a disk-shaped portion at the lower end, and a polishing disk secured to said holder at the center and driven by engagement with the lower surface of the disk-shaped portion of the holder, said holder having flexible walls below said hub for permitting alignment of said polishing disk with the surface being polished.
